CLAIM

The ornamental design for a networking device for a luminaire, as shown and described.

DESCRIPTION

FIG. 1 is a top, front, right side perspective view of a networking device for a luminaire, showing our new design.

FIG. 2 is front elevational view thereof.

FIG. 3 is a rear elevational view thereof.

FIG. 4 is a left side elevational view thereof.

FIG. 5 is a right side elevational view thereof.

FIG. 6 is a top plan view thereof.

FIG. 7 is a bottom plan view thereof.

FIG. 8 is a bottom, front, right side perspective view thereof; and,

FIG. 9 is a top, front perspective view thereof in an exemplary position of use atop a streetlight luminaire.

The broken lines in the drawings are directed to environment and do not form any part of the claimed design.

1 Claim, 5 Drawing Sheets
